CORRUGATED SHEATHING SYSTEMS
Howard H. Nuernberger, Natrona Heights, Pa., assignor
to Aluminum Company of America, Pittsburgh, Pa.,
a corporation of Pennsylvania
Filed Aug. 14, 1959, Ser. No. 833,730
2 Claims. (Cl. 189—88)

This invention relates in general to sheathed structures and is more specifically addressed to an improved system of sheathing employing conventional corrugated sheet members as the principal sheathing material.

An object of the invention is to provide relatively inexpensive sheathed structures, including the walls and roofs of buildings, in which conventional corrugated sheet members are secured to an underlying supporting structure without the necessity of providing special and expensive retaining clips and like fastening elements.

Another object of the invention is to provide a corrugated sheathing system and method of accomplishing the same which can be installed from the exterior surface of the underlying structure supporting the same.

Other objects and advantages of the invention will be fully understood on reference to, and consideration of, the following description and drawings, in which:

FIG. 1 illustrates a fragmentary perspective view of an assembled structure embodying features of the invention;

FIG. 2 illustrates a fragmentary sectional elevation, to enlarged scale, taken on the plane II—II of FIG. 1, and showing incomplete assembly of an overlying corrugated sheet and underlying supporting member therefor; and

FIG. 3 illustrates a view similar to FIG. 2 of a completed assembly in accordance with the practice of the invention.

Basically, the invention relates to sheathed structures in which corrugated sheets are supported and secured to underlying supporting structures without recourse to any materials other than conventional corrugated sheet material and regularly employed conventional securing devices. For example, conventional corrugated sheeting of standard sizes, any one of a number of commercially available conventional blind rivets, nails or similar fastening devices, represent the material requirements in the successful practice of the invention.

Referring to the drawings, for a practical illustration of the invention, 10 represent elements of a structure which is to be enclosed with conventional corrugated sheathing. Studs, rafters, girts, purlins, or similar framing members employed in building construction, satisfy the requirement and conditions fulfilled by the elements 10, their chief purpose being to serve as underlying structure or support for sheathing in the form of corrugated sheets 12.

In the preferred practice of the invention, a retaining strip 14, preferably obtained by shearing a narrow strip from an end of a full sheet 12 across its width transverse to the corrugations, is secured to an exposed surface of each of the members 10. In the case of wood construction, the strip 14 can be nailed directly to members 10, at suitable intervals along its length, with the nails 16 driven through the troughs of the corrugated retaining strip 14. In the case of metallic, or other materials more durable and permanent than wood, for the underlying supporting elements 10, metal screws, rivets, lag bolts, and similar conventional fasteners would be substituted for the nails 16.

The cover sheets 12 are supported on the retaining strips 14 in nested relationship of their complementary corrugations, and suitable fastening devices, such as con-

2

ventional blind rivets 18 extending through superimposed crests of the nested corrugations, are employed to secure the cover sheets 12 to their underlying retaining strips 14. It will be observed on reference to FIGS. 2 and 3 that the blind rivets 18 comprise a tubular, flanged body member 20 inserted through suitable aligned apertures in the over and under nested crests of adjacent corrugations of a sheet 12 and its underlying retaining strip 14, outward withdrawal of the central rod element 22 of the rivet functioning to expand or upset the tubular body 20 against the underside of a crest of the corrugated retaining strip 14 to thereby clamp the cover sheet 12 against and beneath the flange of the body element 20 of the rivet. Blind rivets of this general type are installed and expanded from the exposed or outwardly facing surface of the sheets 12, as above described, to secure the sheathing sheets 12 to their underlying retaining strips 14 and supporting structure therefor.

From the foregoing description it will be evident that 20 a sheathing system and method of sheathing are provided in which corrugated panels or sheet 12 are supported adjacent their ends, and intermediate thereof if required, by underlying corrugated retaining strips 14 with the corrugations of the sheets 12 in nested relationship within 25 the corrugations of the retaining strip 14, the latter strip or strips being, in turn, secured to a permanent framing or supporting structure represented by the elements 10. It will also be manifest that the system in the practice of 30 the invention permits securement of the sheathing sheets by means of conventional blind rivets, or similar devices, entered or introduced through apertures in superimposed or adjacent nested crests of the corrugated sheets 12 and their underlying retaining strips 14 from the outwardly exposed surfaces of the sheets 12. If desired, a washer 35 (not shown) may be provided under the flange of the rivets 20 to act as a seal against moisture through the adjacent connections. The material of the washer would preferably be natural or synthetic rubber or a soft metal such as lead.

Although a single embodiment has been selected for purposes of illustrating and describing the invention, it is to be understood that changes in the shape and sizes of the corrugated covering sheets and complementary retaining strips may be resorted to without departing from the 45 intended scope and spirit of the invention, as hereinafter claimed.

Having described the invention, what is claimed is:

1. A sheathed installation comprising a rigid underlying supporting structure composed of parallel spaced framing members, corrugated sheathing sheets of identical configuration in respect of their corrugations in a transverse plane through the same, narrow retaining strips severed from at least one of the corrugated sheets transversely through the corrugations thereof and secured to coplanarly disposed flat surfaces of the parallel spaced framing members of the supporting structure by fasteners confined to passing through troughs of the retaining strips and entering the aforesaid flat surfaces of the framing members of the supporting structure in contact with the underside of the troughs, the secured retaining strips constituting uniform directional disposition, alignment and configuration of their corrugations with the crests thereof forming through clearance between the flat coplanar surfaces of the spaced parallel frame members in the axial direction of the corrugations, the sheathing sheets being received in nested registration of their corrugations with the corrugations of the underlying secured retaining strips, headed fasteners inserted through aligned apertures in nested crests of the registered sheathing sheets and underlying 55 secured retaining strips from exposed surfaces of the crests of the sheathing sheets, and said headed fasteners

3

being manipulated from the exposed surfaces of the crests of the sheathing sheets to upset extending free ends thereof within the clearance spaces formed between the underlying supporting structure and crests of the retaining strips to provide a unitary sheathed installation.

2. A sheathed structure comprising a plurality of parallel spaced members constituting an underlying supporting structure to be sheathed, said spaced members presenting flat surfaces lying in the same plane, an identical retaining strip secured to the coplanar flat surfaces of each of the spaced members, each retaining strip being of corrugated configuration with the corrugations thereof in alignment and its securing means confined to passing through troughs of corrugations of the strip in bearing contact on the coplanar flat surface of its supporting member, the crests 15 of each retaining strip so secured providing through clearance in the axial direction of the corrugations between

the crests and plane flat surface of the supporting member underlying the same, a covering sheet having corrugations complementary to the retaining strips disposed in nested relationship thereover, fasteners inserted through aligned apertures in nested crests of the complementary corrugations of the covering sheet and retaining strips from the exposed surface of the covering sheet, and said fasteners being manipulated from the exposed surface of the covering sheet to upset the ends thereof beneath the crests of 10 the retaining strips.
